UNITED STATES PATENT OFFICE.

ROY R. BARNARD, OF LONG BEACH, CALIFORNIA.

SASH FASTENER.

Application filed January 12, 1927. Serial No. 160,688.

This invention relates to sash fasteners and has for an object the provision of a device which will combine with its fastening features, the features of a window wedge or 5 anti-rattle and thus serve a twofold purpose, first, that of fastening the window in a desired position, and, second, to prevent objectionable rattling noises in windy weather.

To this end, the invention provides a novel 10 form of fastening and anti-rattling device arranged to be carried by one of the sash of a window and to engage a keeper element secured to the other sash, the construction of the keeper element enabling the sash to be 15 fastened in any desired position.

With the above and other objects in view, the invention further includes the following 20 novel features and details of construction, to be hereinafter more fully described, illustrated in the accompanying drawings and pointed out in the appended claim.

In the drawings:—

Figure 1 is a fragmentary elevation showing a portion of a window with the invention 25 applied.

Figure 2 is an enlarged fragmentary view of the adjacent portions of the upper and lower sash with parts shown in section.

Figure 3 is an enlarged fragmentary section 30 taken substantially on the line 3—3 of Figure 1.

Figure 4 is a detail perspective view of the fastener housing.

Referring to the drawings in detail wherein 35 like characters of reference denote corresponding parts, the reference character 10 indicates a portion of a window frame in which is slidably mounted an upper sash 10 and a lower sash 11, all of which may be 40 of the usual or any preferred construction.

Secured to the upper sash by means of 45 screws or similar fastening devices 12, is a metal strip 13, the latter being provided with spaced openings 14. This strip is of any desired width and length, but preferably extends throughout the length of the sash to which it is attached.

Secured to the lower sash 11 is an angle plate 15 which is provided at its upper end 50 with an extension 16. This extension is

adapted to overlie the strip 10 and is provided with an opening 17 in which is secured a cup-shaped housing 18. The housing may be secured by any suitable means, such as by forming an annular groove 18 in the open end 55 of the housing to engage over the edge of the opening 17, as is clearly shown in Figures 3 and 4 of the drawings. The housing 18 has its open end disposed toward the strip 13 and its outer end is provided with an opening 60 19. Extending through the housing 18 is a pin 20 whose inner end is adapted to engage in any one of the openings 14. The pin 20 is provided with a collar 21 and surrounding the pin between this collar and the end of the housing 18 is a coiled spring 22. This spring acts to yieldingly force the pin inward so as to engage within the openings 14. The outer end 65 of the pin 20 is provided with a head or 70 knob 23, by means of which it may be withdrawn from the openings and in order to hold the pin in withdrawn position, the knob has extending therefrom one or more lugs 24. These lugs are adapted for passage through 75 extensions 25 upon opposite sides of the opening 19 and when the lugs are withdrawn from these extensions they may be positioned against the end of the housing so as to prevent inward movement of the pin.

If desired, the upper sash may be provided 80 with a channel 26 which extends longitudinally beneath the strip 13.

The invention is susceptible of various 85 changes in its form, proportions and minor details of construction and the right is herein reserved to make such changes as properly fall within the scope of the appended claim.

Having described the invention what is 90 claimed is:—

In combination with upper and lower relatively slidable sash, a strip adapted to be secured to one of the sash and having longitudinally spaced openings therein, a plate secured to the other sash and having an extremity bent over the top of the sash and then upwardly to overlie the strip, said extremity having an opening therein, a cup-shaped housing having its open end surrounded by an annular groove to receive the walls of said 95 100 strip.

opening secured and disposed toward the strip and having an opening in its outer end, a shouldered pin extending through the housing and having its inner end adapted to engage within the openings of the strip, a spring surrounding the pin between the shoulder thereof and the end of the casing to force the pin inward, a knob upon the outer end of the pin and means carried by the knob to engage the casing and hold the pin disengaged from the strip.

In testimony whereof I affix my signature.

ROY R. BARNARD.
